CLAIM

The ornamental design for a combined product display and refrigerator, as shown and described.

DESCRIPTION

FIG. 1 is a perspective view of a combined product display and refrigerator showing my new design, the refrigerator depicted in phantom and forming no part of the claimed design;

FIG. 2 is a top view thereof;

FIG. 3 is a frontal view thereof, the rear view being a mirror image;

FIG. 4 is a left side view thereof;

FIG. 5 is a right side view thereof; and,

FIG. 6 is a bottom view thereof.
